UNITED STATES PATENT OFFICE.

HARRY E. GILBERT, OF BRIDGEPORT, CONNECTICUT.

STILL.

Application filed March 20, 1925. Serial No. 16,906.

Fig. 1 is a front view of a still constructed in accordance with my invention.

Fig. 2 is a transverse sectional view of the same.

5 Fig. 3 is a side view, partly in section.

Fig. 4 is a plan view, with the container removed.

Fig. 5 is a broken, sectional view of one end of a tubular container.

10 This invention relates to improvement in stills particularly adapted for refining petroleum or chemical compounds. In treating material in a still, it is desirable that the heat should be evenly developed beneath

15 the container, and the object of this invention is to so form the top of the fire-box that the heat, as it reaches the container, will be equalized, and the invention consists in

19 the construction as hereinafter described and

20 particularly recited in the claims.

In carrying out my invention, I employ a container 10, herein shown (in Fig. 3) as a long, cylindrical container, suitably supported between side walls 11 and 12, so as

25 to form a chamber 13 between the bottom of the container and the top of the fire-box 14. This top of the fire-box is divided into a plurality of sections, herein represented as three in number. The first zone 15 is

30 formed from siliceous material in one of its various forms, and is relatively thick, so as to resist radiation of heat from the front part of the fire-box where the burner enters, preferably through a mouth 16. The second

35 zone 17 is comparatively thin and formed from siliceous material, while the third zone 18 is formed with a series of openings 19, through which flames from the burner may

40 directly pass into the chamber 13, through which they extend forward into the flue 20.

The section 15, which tends to resist radiation, is over the front portion of the fire-box, where the greatest heat exists; the zone 17 over the central part, where there is less

45 degree of heat, but being relatively thin, will give the desired radiation into the chamber 13; while the zone 18, provided with holes, permits the direct action of the flames against the rear part of the container,

50 and by thus passing forward, equalizes the heat in the chamber 13, so as to maintain substantially the same temperature throughout the length of the container.

As herein shown, the fire-box is divided

55 by longitudinal partition 21 forming two separate fire-boxes, and it is obvious, without

illustration, that the number of fire-boxes may be increased as desired, according to the size of the container. But in every case, the top of the fire-box or boxes will be 60 formed in zones, giving different degrees of radiation into the container-chamber, and it is also obvious that more than three zones might be employed of different substances, so as to vary the radiation and equalize the 65 heat in the container-chamber.

Instead of using a cylindrical container, I may use a tubular container, as shown in Fig. 5 of the drawings, which, like a tubular boiler, has a plurality of tubes 23 mounted 70 in headers 24, and through which tubes the material to be heated will circulate.

As before stated, any approved form of burner may be employed, but in any case, the top of the fire-box will have differential 75 radiant properties upward toward the surface of the container in a substantially direct line. At the same time, provision is made for a practically perfect consumption of the fuel used in heating. 80

I claim:

1. In a still, the combination of a container substantially horizontally disposed, a firebox having a top in spaced relation to the bottom of the container, a burner at the 85 forward end of the firebox, the top of the firebox being divided in zones of heat-conducting qualities of various degree, the zone nearest the burner being the least heat-conducting and the zones more remote from 90 the burner progressively greater heat-conducting, for the purpose of making the said top uniformly radiant.

2. In a still, the combination of a container substantially horizontally disposed, a firebox having a top in spaced relation to the bottom of the container, a burner at the 95 forward end of the firebox, the top of the firebox being divided in zones of heat-conducting qualities of various degree, the zone nearest the burner being the least heat-conducting, the zones more remote from the burner progressively greater heat-conducting, and those furthest removed from the burner formed with perforations, for the 100 purpose of making the said top uniformly radiant.

3. In a still, the combination of a container, a firebox having a top in spaced relation to the bottom of the container, the 110 said container being substantially horizontally disposed and being supported above

the said firebox so as to form a chamber between them, a burner at the forward end of the firebox, the top of the firebox being divided in zones of heat-conducting qualities of various degree, the zone nearest the burner being the least heat-conducting and the zones more remote from the burner progressively greater heat-conducting, for the purpose of making the said top uniformly 10 radiant.

4. In a still, the combination of a container substantially horizontally disposed, a

firebox having a top in spaced relation to the bottom of the container, a burner at the forward end of the firebox, the top of the firebox being divided in three zones, the zone nearest the burner being relatively thick, the zone adjacent to it and further away from the burner being relatively thin, and the zone furthest removed from the burner formed with perforations.

In testimony whereof, I have signed this specification.

HARRY E. GILBERT.
